UNITED STATES PATENT OFFICE.

RALPH M. LOVEJOY, OF BOSTON, MASSACHUSETTS, ASSIGNOR TO LEWIS-SHEPARD COMPANY, OF WATERTOWN, MASSACHUSETTS, A CORPORATION OF MASSACHUSETTS.

TRANSPORTING MECHANISM FOR HOISTING MACHINES.

Original application filed July 12, 1922, Serial No. 574,517. Divided and this application filed February 7, 1925. Serial No. 7,507.

This invention relates to improvements in transporting means for hoisting machines and the object thereof is to provide a hoisting machine comprising a frame having one end supported upon anti-friction ground-contacting supports and the other end upon frictional ground-engaging supports with a wheel steering mechanism having a tongue and operable by the vertical swinging movement of the tongue when the tongue is in any steering position to raise and to support the front end of the frame out of engagement with the ground, whereby the machine can be readily transported from one place to another.

A further object of the invention is to provide a steering mechanism for the front end of a hoisting machine of the character described with lifting mechanism operable by the vertical swinging movement of the tongue which will lift and support the front end of the frame upon the steering mechanism and permit the handle to be freed for the purpose of freely steering the truck.

A further object of the invention is to provide a lifting mechanism for the front end of the truck of the character described in which the handle may be employed not only to pull the machine, but also to push the machine when the front end of the frame is raised and supported out of engagement with the ground.

More specifically the object of the invention is to provide a hoisting machine comprising a frame having wheels for supporting the rear end of the frame and legs normally supporting the front end of the frame with a steering wheel having a post rotatably and axially mounted on the frame and provided with a steering tongue with lifting means operable by the vertical swinging movement of the tongue to move the steering post axially relatively to the frame and thereby raise the front end of the frame free from the ground when the tongue is in any steering position, thereby permitting the hoisting machine to be transported from place to place.

Another specific object of the invention is to provide a lifting mechanism comprising a toggle construction operable by the vertical swinging movement of the tongue which will serve not only to lift the front end of the frame free from the ground, but also to

lock the same in elevated position and permit the handle to be released from the steering mechanism in order that it may be free to swing vertically and conveniently used to steer the truck. 55

Other objects and features of the invention will more fully appear from the following description and the accompanying drawings and will be particularly pointed out in the claims. 60

The present application constitutes a division of my prior application No. 574,517 for improvements in hoisting machines filed July 12, 1922. 65

The preferred embodiment of the invention is illustrated in the accompanying drawings, in which, 70

Fig. 1 is a side elevation of an elevating truck of the "tiering machine" type embodying the invention, the hoisting mechanism being omitted;

Fig. 2 is a detail side elevation upon an enlarged scale of a portion of the frame, the steering mechanism and lifting mechanism operable by the tongue, showing the same as supporting the frame in elevated position with the tongue connected to the lifting mechanism, a portion of the tongue being shown in vertical section; and, 75

Fig. 3 is a similar view showing the tongue disconnected from the elevating mechanism. 80

The invention is disclosed herein as embodied in a hoisting machine of the type generally known as "tiering machines," but it will be understood that it is equally applicable to other forms of hoisting devices such as hand trucks adapted to be placed beneath a device to be transported and the frame of the hoisting device raised thereby raising the device to be transported from its engagement with the ground or floor after which it may be drawn or pushed to any desired place and again deposited upon the ground or floor. 85 90 95

The hoisting device illustrated in the accompanying drawings comprises a main frame having side bars 1, preferably of channel form, connected by a central transverse girder 2 which preferably is also of channel form and rests upon and is secured to the inner flanges of the side bars 1, and a front transverse girder 3 which preferably is of channel form and rests upon and is secured to the upper flanges of the side bars 1. 100 105

Brackets 4, secured to the rear ends of the side bars 1, are provided with suitable journals to receive a shaft 5 having wheels 6 which support the rear end of the frame. A pair 5 of legs 7, which are secured to the front cross girder 3, normally serve to support the front end of the frame. A pair of vertical guiding standards desirably are supported centrally of the main frame and are secured to 10 the cross girder 2. These standards desirably are made in foldable sections connected by hinges.

As illustrated herein the upper ends of the lower sections 8 of the standards are provided with forwardly extending hinge members 9 which are pivotally connected by a transverse shaft 10 to a complementary pair of hinge members 11 which are similarly secured to the lower ends of upper standard sections 12 which are adapted when in vertical position to rest upon the upper ends of the sections 8 and extend in axial alinement therewith. Brace rods 13 desirably are connected at their upper ends to the shaft 10 and at their 25 lower ends fixedly secured to the side bars 1.

Suitable means are provided for detachably securing the standard sections in vertical alinement. The locking means, however, forms the subject matter of a divisional application and need not be described herein.

Load supporting means are arranged to be moved vertically upon and guided by the vertical standards and suitable hoisting mechanism is provided for elevating the load 35 supporting means.

In the preferred construction illustrated herein the load supporting means is in the form of a carriage having a vertically movable frame slidably mounted upon said standards and provided with a horizontal platform. The carriage frame comprises vertical side members 14, preferably channel bars, which are located upon the outsides of the vertical standards and adjacent thereto and 40 are connected by cross members 15 and 16. The carriage frame also comprises L-shaped platform supporting members the vertical arms 17 of which are riveted to the vertical members 14 and the horizontal members 18 of 45 which form the girders of the platform. The platform may be provided with any suitable support for the articles which are to be elevated. As illustrated herein a pair of angle plates 19 and 20 rest upon and connect the 50 girders 18 and are provided with journals to receive a series of rollers 21 which enable heavy articles readily to be loaded upon and unloaded from the platform.

Flanged wheels 22 mounted upon suitable 60 brackets on the girders 14 are arranged to engage the rear face of the vertical standards 8 and flanged wheels 23 mounted in suitable brackets 24 upon the side members 14 of the carriage engage the front faces of the vertical standards, thus providing anti-friction

means for supporting and guiding the platform in its vertical movement.

Any suitable means may be employed for raising the platform such as a cable 25 attached to the platform carriage and passing over a sheave 26 suitably mounted at the upper end of the standard sections 12 with a suitable windlass (not shown) for winding up and unwinding the cable. The hoisting mechanism desirably is of the character disclosed in the prior application of which the present application is a division and need not be described herein.

The present invention relates particularly to a novel mechanism for raising the front 80 end of the frame so that it will be supported upon suitable steering mechanism with the legs 7 of the frame removed from the floor a sufficient distance to permit the hoisting machine to be transported from place to place 85 as a truck either when loaded or unloaded.

As illustrated herein the steering mechanism comprises a front steering wheel 27 which is mounted upon an axle 28 in the fork 29 of a steering post 30 which is rotatably and 90 slidably journaled in a bracket 31 which preferably is secured to a standard 32 which is mounted at its lower end upon the cross girder 3 and is connected at its upper end by suitable framework 33 to the vertical standards 8. The framework may be employed to support a suitable motor for actuating the windlass as is disclosed in the original application of which this is a division.

A collar 34 is fixedly secured to the upper 100 end of the steering post 30 and is provided with a pair of upwardly extending ears 35 which carry a transverse shaft 36 upon which the steering tongue and a member of the lifting mechanism for the frame is pivotally 105 mounted.

The steering tongue desirably is made in telescopically movable sections one of which comprises a tubular member 37 having arms 38 which are pivotally mounted upon the shaft 36 outside of the ears 35 on the collar 34. The arms 38 desirably are provided with extensions presenting shoulders 39 so formed as to engage stop shoulders 40 upon the collar when the tongue is raised nearly to vertical position. The engagement of the shoulders 39 of the arms 38 with the stops 40 serve to prevent the steering tongue from swinging upwardly beyond a predetermined distance and also provide means for arresting the upward movement of the tongue in a position in which it can be used to push the truck rearwardly when the handle is in any steering position.

The other section 41 of the tongue, which desirably is of tubular form and provided with the usual transverse handle 42, is slidably mounted at its lower end in the tubular member 37. The tongue member 41 is provided with a transversely extending pin 43 which

extends into oppositely disposed slots 44 in the tubular member 37 so that the tongue section 41 may have a short longitudinal telescopic movement relatively to the tubular member 37 of the tongue. The purpose of this longitudinal movement is to provide means for releasably locking the vertical swinging tongue to the lifting mechanism when it is desired to raise or to lower the front end of the frame as will be hereinafter more fully described.

The invention contemplates broadly the provision of means operable by the vertical swinging movement of the tongue to cause relative longitudinal movement between the frame and the steering wheel which will elevate the front end of the platform to a sufficient height to raise the legs 7 of the frame the desired distance from the ground or floor.

The preferred form of lifting mechanism for the front end of the frame, which is illustrated herein, comprises a toggle construction consisting of a bell crank lever 45 which is pivotally mounted upon the shaft 36 of the steering post ears, one end of the bell crank lever being flexibly connected to the frame, preferably to the standard 32, and the other arm of the bell crank lever being adapted to be detachably connected to the steering tongue. In the construction illustrated the rearwardly extending arm of the bell crank lever is pivotally connected to the lower end of a link 46 the upper end of which is pivotally connected to a swivel 47 the stem 48 of which is rotatably mounted in a bracket 49 which is secured to the vertical standard 32. The axis of the stem 48 of the swivel desirably is in alinement with the axis of the steering post. The other arm 50 of the bell crank lever is so constructed and positioned as to engage a shoulder 51 upon the inner end of the tubular member 37 of the steering tongue. The member 41 of the steering tongue when forced inwardly as far as is permitted by the sliding movement of the pin 43 in the slot 44 engages beneath the end of the bell crank arm 50 and thereby locks said arm securely to the steering tongue.

In the normal position of the hoisting machine when the legs 7 are resting upon the floor the pivotal connection between the end of the bell crank lever and the link 46 is swung inwardly toward the frame of the hoisting machine in such a manner as to collapse the toggle as illustrated in Fig. 1. The legs of the frame thus resting upon the ground or floor will prevent movement of the truck during the raising and lowering of the platform. When the frame of the truck is thus in lowered position the shoulder 51 of the tubular tongue section 37 is engaged by the arm 50 of the bell crank lever and the tubular member 41 of the tongue retained in elevated position as illustrated in Fig. 1, the sliding member 41 of the tongue normally be-

ing held in its downwardly telescoped position by the force of gravity. When it is desired to raise the front end of the frame upon the steering mechanism to lift the legs 7 from the floor so that the hoisting machine can be transported from place to place, the operator swings the tongue downwardly thereby rocking the bell crank lever 45 about its pivot until the pivotal connection of the arm of the bell crank lever to the link 46 swings across the plane of the axes of the steering post 30 and swivel stem 48 (which are in substantial alinement) and until the arm 50 of the bell crank lever engages a shoulder or stop 52 upon the steering post head 34. The toggle is therefore locked in extended position.

During this movement of the tongue a relative movement is produced between the steering mechanism and the frame and as the wheels of the steering mechanism rest upon the floor the frame is consequently raised from the floor and its weight supported upon the steering mechanism. When the frame is thus raised and the toggle locked in extended position the slidably member 41 of the tongue may be pulled end-wise so that its end will pass from beneath the end of the arm 50 of the bell crank lever. Thus the tongue is freed from the lifting mechanism and can be raised and lowered as well as swung laterally and may be used conveniently for pulling, pushing or steering the truck without disturbing the position of the lifting mechanism. When it is desired to push the truck backwardly the tongue is raised until the shoulders 39 in the ends of the tongue arms 38 engage the shoulders or stops 40 upon the steering head which prevent further upward movement of the tongue and therefore permit the pushing of the truck when the tongue is in any steering position.

It will be understood that the embodiment of the invention herein is of an illustrative character and is not restrictive and that the mechanisms herein claimed may be adapted for other purposes than in a hoisting machine within the spirit and scope of the following claims.

Having thus described the invention, what is claimed as new, and desired to be secured by Letters Patent, is:

1. A hoisting machine comprising a frame having rear wheels and front legs to engage the ground, steering mechanism comprising a vertical steering post mounted on the front end of the frame and rotatably and axially movable, a steering tongue pivotally connected to said steering post to have a vertical swinging movement and lifting means, including a swiveled strut having means connecting its upper end to the frame in substantially axial alinement with the axis of the steering post and a member mounted on said steering post engaging the lower end of said strut and provided with means detachably en-

gaging said tongue and operable, when so engaged, by the vertical swinging movement of the tongue when in any steering position to move said frame axially relatively to said steering post and thereby raise the front end of said frame and support the same upon said steering mechanism.

2. A hoisting machine comprising a frame having rear wheels and front legs, steering mechanism comprising a vertical steering post mounted on the front end of said frame and rotatably and axially movable, a steering tongue pivotally connected to said steering post to have a vertical swinging movement, lifting means including a swivel strut having means connecting its upper end to the frame in substantially axial alignment with the axis of the steering post and having a member mounted on said steering post engaging the lower end of said strut provided with means normally positioned to be engaged by said tongue when said tongue is swung vertically upwardly with the frame in lowered position and operable, by the downward vertical swinging movement of the tongue, when in any steering position, to move said steering post downwardly and thereby raise the front end of the frame, so that said frame is carried upon the steering mechanism, and means for releasing said tongue from engagement with said lifting means to permit free steering movement of said tongue.

3. A hoisting machine comprising a frame having rear wheels and front legs, steering mechanism comprising a vertical steering post mounted on the front end of said frame and rotatably and axially movable, a steering tongue pivotally connected to said steering post to have a vertical swinging movement, a toggle mechanism connecting said steering post to said frame and having means releasably to engage the tongue and operable, when so engaged, by the vertical swinging movement of said tongue when in any steering position to straighten said toggle and raise the front end of said frame and when straightened to support the same upon the steering mechanism.

50 4. A hoisting machine comprising a frame having rear wheels and front legs, steering mechanism comprising a vertical steering post mounted on the front end of said frame and rotatably and axially movable, a steering tongue pivotally connected to said steering post to have a vertical swinging movement, a toggle mechanism connecting said steering post to said frame and operable by the vertical swinging movement of said tongue when in any steering position to straighten said toggle and raise the front end of said frame and when straightened to support the same upon the steering mechanism and means for disengaging said tongue from said toggle mechanism when the front end of the frame

is supported in elevated position whereby the tongue may be freed to permit the pulling or pushing of the truck in any direction.

5. A hoisting machine comprising a frame having rear wheels and front legs, steering mechanism comprising a vertical steering post mounted on the front end of said frame and rotatably and axially movable, a steering tongue pivotally connected to said steering post to have a vertical swinging movement, a toggle mechanism connecting said steering post to said frame and operable by the vertical swinging movement of said tongue when in any steering position to raise the front end of said frame and support the same upon the steering mechanism, means for disengaging said tongue from said toggle mechanism when the front end of the frame is supported in elevated position and means upon said tongue operable to engage said steering post when the tongue is raised to permit the truck to be pushed with the tongue in any steering position.

6. A hoisting machine comprising a frame having rear wheels and front legs, steering mechanism having a vertical steering post mounted in said frame and rotatably and axially movable, a vertically swinging steering tongue comprising a section pivotally mounted on said steering post and a section movable longitudinally relatively to said pivotally mounted section, lifting means comprising a member pivotally mounted upon said steering post and connected to said frame and adapted to be detachably engaged between said pivotally mounted steering tongue section and said longitudinally movable steering tongue section when the latter is in a predetermined position and operable by the vertical movement of said tongue to raise the front end of said frame and support the same upon said steering mechanism.

7. A hoisting machine comprising a frame having rear wheels and front legs, steering mechanism having a vertical steering post mounted in said frame and rotatably and axially movable, a vertically swinging steering tongue comprising a tubular section pivotally mounted on said steering post and a section telescopically movable within said pivotally mounted section, lifting means comprising a member pivotally mounted upon said steering post and connected to said frame at one end and having its other end positioned to be engaged by said tongue sections when telescopically moved to a predetermined shortened position, whereby said lifting means is operable by the vertical swinging movement of the tongue to raise the front end of said frame and support the same upon said steering mechanism.

8. A hoisting machine comprising a frame having rear wheels and front legs, steering mechanism having a vertical steering post mounted on said frame and rotatably and

axially movable, a vertically swinging steering tongue comprising a section pivotally mounted on said steering post and a section movable longitudinally relatively to said pivotally mounted section, a lifting toggle mechanism connected to said steering post and said frame having means positioned to be engaged between the pivotally mounted section and the end of the longitudinally movable section of the tongue when the latter is in a predetermined position, whereby a vertical swinging movement of the tongue will actuate the toggle mechanism to raise the front end of the frame and support the same upon the steering mechanism, said tongue being adapted to be released from engagement with said lifting toggle mechanism by longitudinal movement of the movable tongue section when the frame is supported upon the steering mechanism.

9. A hoisting machine comprising a frame having rear wheels and front legs, steering mechanism having a vertical steering post mounted on said frame and rotatably and axially movable, a vertically swinging tongue pivotally mounted upon said steering post, lifting toggle mechanism comprising a bell crank lever pivotally mounted on said steering post to swing about a horizontal axis, a link connected at one end to one arm of said bell crank lever and pivotally connected at its other end to the frame by a swivel the axis of which is in axial alinement with the axis of the steering post, means on said tongue operable detachably to engage the other arm of said bell crank lever and by vertical swinging movement of said tongue to actuate said toggle mechanism to raise the front end of the frame relatively to the steering mechanism and means for limiting the movement of said bell crank lever when the

pivotal connection between the arm of said bell crank lever and said link has passed beyond the axial line of said steering post and swivel. 45

10. A hoisting machine comprising a frame having rear wheels and front legs, steering mechanism having a vertical steering post mounted on the front end of said steering frame and rotatably and axially movable, a vertically swinging tongue comprising a tubular section pivotally mounted on said steering post and a section telescopically mounted in said tubular section, lifting toggle mechanism comprising a bell crank lever pivotally mounted on said steering post to swing about a horizontal axis, a link connected at one end to one arm of said bell crank lever and pivotally connected at its other end to the frame by a swivel the stem of which is in axial alinement with the axis of the steering post, the other end of said bell crank lever being positioned to be engaged by the relatively movable telescoping members of said tongue, whereby the vertical swinging movement of said tongue will actuate said toggle mechanism to raise the frame relatively to the steering mechanism and means for limiting the movement of said bell crank lever when the pivotal connection between the arm of said bell crank lever and link has passed beyond the line of the axes of said steering tongue and swivel, whereby the front end of the frame will be supported upon said steering mechanism and disengagement between the tongue and bell crank lever permitted by relative longitudinal movement of the telescoping members of said tongue. 55 60 65 70 75

In testimony whereof, I have signed my name to this specification.

RALPH M. LOVEJOY.
